UNITED STATES PATENT OFFICE.

LESLIE CARL DUTRO, OF LONG BEACH, CALIFORNIA.

OIL CUP

Application filed September 6, 1922. Serial No. 586,486.

To all whom it may concern:

Be it known that I, LESLIE C. DUTRO, a citizen of the United States, and a resident of Long Beach, in the county of Los Angeles and State of California, have invented a new and Improved Oil Cup, of which the following is a full, clear, and exact description.

- This invention relates to improvements in oil cups and more particularly to cups having an automatic feed controlled by the temperature of the bearings or by the temperature of certain parts of the machine either adjacent or at a distance from the cup.
- Another object of the invention is the provision of an oil feeding device capable of use in different positions and in any position automatically feeding the necessary quantity of oil from time to time.
- A still further object of the invention is to provide an automatic oil feeding device which may be arranged on a stationary bearing or stationary part or may be arranged on a rotating member.
- In the accompanying drawings—
- Figure 1 is a longitudinal vertical section through an oil cup and part of a bearing, the oil cup disclosing one embodiment of the invention.
- Figure 2 is a longitudinal vertical section through a further modified form of oil cup illustrating how the cup may supply oil automatically to a bearing from an appreciable distance above the bearing.
- Referring to the accompanying drawings by numeral, 11 indicates an oil cup which is provided with a top 12 and a bottom 13 of substantially identical structures, said top and bottom being supplied with gaskets 14 and 15 whereby tight joints are produced. Preferably the tubular section 16 between the top and bottom is formed of glass. The top 12 is provided with an aperture through which a central filler tube 17 extends, said tube being threaded exteriorly at both ends. A suitable nut 18 is used at the upper end for clamping the tube securely to the top 12 while a covering cap 19 is threaded onto the extreme end of the filler tube 17. Suitable gaskets or washers are arranged beneath the cap 19 and the nut 18 respectively whereby there will be no chance of any leakage. The lower end of the tube 17 extends through the bottom 13 and is threaded into a fitting or nipple 20 which
- is also exteriorly threaded so as to be screwed into the bearing 21. The fitting 20 is provided with a large bore for receiving the lower threaded end of tube 17 and a small bore for receiving the threaded end of the lubricant feed tube 22. In my prior Patent No. 1,408,180, a well was formed in an extension from the bottom of the cup but in the present instance the well is formed in the lower part of the tube 17 by using a plug 23 arranged below the lowermost apertures 24. It will be noted that there are several of these apertures provided in the filler tube 17 and the top aperture is an appreciable distance below the top 12 so that an air chamber is insured in the upper portion of the cup even though a careless operator might overflow the tube 17 in filling the cup.
- When the parts have been constructed as shown in Figure 1 with the plug 23 in place, a well 25 is produced, said plug being arranged a short distance above the top of the lubricant feed tube 22. By this construction and arrangement, oil is permitted to flow into the well through the orifice 26 until the oil level is approximately as shown in Figure 1 thus confining a quantity of air in the upper part of the well. The openings 24 in the tube 17 are formed so as to permit the filling of the cup and filler tube to replace the lubricant which is fed from the cup. It will be noted that the filler tube may be readily removed as occasion may require.
- The operation of the cup is entirely automatic. When the cup is filled or partially filled with lubricant, a portion thereof will flow into the well 25 as shown in Figure 1, but due to the fact that the cup 11 is airtight, the escape of oil from the cup will cause a partial vacuum to be formed in the upper portion so that the oil will cease to flow under normal conditions. When the temperature of the bearing increases, the heat will be transmitted to the well cup and lubricant to cause an expansion of the lubricant and also an expansion of the air. This expansion will force the lubricant downwardly into the well 25 through the orifice 26 which oil will overflow through the tube 22 into the bearing 21 to cool the latter. As the temperature decreases, the expansion of the fluid will decrease and if this decrease in temperature is sufficient, the lubricant

will be sucked back from the well 25 through the orifice 26 and air will be drawn from the bearing through the tube 22 into the well. The feed of lubricant is, therefore, controlled automatically by the temperature of the bearing and in carrying out this automatic operation, the metal part of the cup becomes heated with the bearing and this heat is transmitted directly to the oil. The amount of expansion of the metal in the cup is so small as not to noticeably affect the capacity of the cup, especially as the walls of the cup are made of glass. However, the heat transmitted is of importance in that it will cause the oil and the air to expand to an appreciable extent. The lubricant and the air expand and contract in accordance with the temperature of the bearing so that the feed of lubricant is automatically maintained and air is drawn into the well and cup from the bearing to maintain the normal atmospheric pressure within the cup. The use of the well 25 allows leeway in the operation of the cup. This leeway is accomplished by extending or shortening the tube 22. By lengthening the tube 22 so that it terminates above the bottom of the well and near the plug 23, the well has to be filled up to a point level with the top of this tube before it begins to feed to the bearing and when the contraction takes place in the well the liquid is drawn up into the cup until the tube 22 is free of oil, when direct communication with the atmosphere is made through the tube 22 and bearing 21. A further advantage of the enclosed well is that when the cup is jarred or shaken, instead of shaking a few drops directly out into the bearing, they are shaken from the cup into the well and when the balance is established this excessive lubricant is drawn back into the cup instead of drawing in air and the original balance is established without any loss of oil or lubricant.

In some machinery, it is found that oil cups are necessary at very inconvenient places and sometimes at places which are almost inaccessible. When this occurs a structure substantially as shown in Figure 2 may be used wherein it will be seen that the oil cup 11 is placed an appreciable distance above the bearing 39. In this form of the invention, the oil cup could not only be placed above the bearing but could be placed above and on one side and still operate in an efficient manner. The cup 11 in this form of the invention is identical to that shown in Figure 1 except the tube 22' is of greater length and also the fitting 20 screws into a pipe 40 instead of a bearing. The pipe 40 is secured in any suitable manner to an air-tight box 41 preferably formed of metal and resting on the bearing 39. It will be noted that the pipe 40, acts merely as a support for the cup 11. A very small pipe 42 connects the air-tight box 41 and the upper part of the cup 11 so that the expansion and contraction of the air in the box 41 will act in a similar manner to that shown in Figure 1. It will be noted that in this form of the invention, as well as in the other form, the variation of heat either on the bearing or some other objects will vary the feeding action of the cup and that all the excess oil is withdrawn into the cup.

What I claim is:—

1. In a lubricating device, an oil cup adapted to be secured to a bearing to be lubricated, a filling tube in the cup and having a partition forming a well in its lower end, the tube being apertured to permit the oil in the cup to enter the said tube and its well, and a feed tube extending into the well above its communication with the cup. 80
2. In a lubricating device, an oil cup provided with a fitting adapted to be secured to a bearing to be lubricated, a filling tube secured in the cup with its lower end extending into the fitting, said tube being provided with a partition forming the lower end of the tube into a well and with openings in its upper end and an opening adjacent the bottom of the cup, and a small feed tube extending through the fitting into the well of the filling tube. 90
3. A lubricant feeding device for bearings, comprising a fitting adapted to be secured to a bearing, said fitting having a comparatively small bore therein, a filler tube secured to said fitting, a cup surrounding said filler tube, means for clamping the cup against said fitting and in position around said filler tube, said means including a closure, said filler tube having a well in its lower end and provided with an aperture adjacent to the bottom of the cup and establishing communication between the cup and a well, and a discharge tube connected with the fitting so as to discharge through the aperture therein, said discharge tube extending into the well and beyond said aperture. 100
4. A lubricant feeding device for bearings, comprising a box forming an air chamber and adapted to be secured upon a bearing to be lubricated, an oil cup provided with a filler tube and a well at the lower end of the said tube, said tube and well communicating with the oil cup, means for mounting the cup on said box, a discharge tube extending from the bearing into the well, and an air tube leading from the said box into the upper part of the oil cup. 115
5. A lubricant feeding device for bearings, comprising a box forming an air chamber adapted to fit against a bearing to be lubricated, a supporting member carried by said box, an oil cup carried by said supporting member, said oil cup being air-tight and provided with a filler tube extending there- 120

through, a plug arranged in said filler tube for causing the lower part of the tube to become a well, said tube being provided with an orifice below said plug, and a plurality 5 of apertures above the plug, a discharge tube extending from said bearing into said well and above the orifice opening therein, and an air tube extending from said box to the upper part of said oil cup whereby the expansion and contraction of air in said box ¹⁰ will provide increasing and decreasing pressure in said oil cup.

LESLIE CARL DUTRO.
